UNITED STATES PATENT OFFICE.

GUY D. STINSON, OF OXNARD, CALIFORNIA.

CHECK-PROTECTOR.

1,262,401.

Specification of Letters Patent. Patented Apr. 9, 1918.

Application filed October 3, 1917. Serial No. 194,570.

To all whom it may concern:

Be it known that I, GUY D. STINSON, a citizen of the United States, residing at Oxnard, in the county of Ventura and State 5 of California, have invented new and useful Improvements in Check-Protectors, of which the following is a specification.

This invention relates to a check protector.

The principal object of this invention is 10 to provide a device which is simple in its construction and the mode of operation and will effectively prepare a check to prevent the amount inscribed thereupon from being raised.

15 Other objects will appear hereinafter.

The invention is illustrated, by way of example, in the accompanying drawings in which:

Figure 1 is a fragmentary view in perspective illustrating a check and further disclosing the protector in operation.

Fig. 2 is a view in section and elevation illustrating the protector as fitted with self-inking means.

25 Referring more particularly to the drawings, 10 indicates a stamp wheel around the periphery of which is disposed a rubber tire 11. The outer face of this tire is formed with an embossed surface adapted to make

30 any desired imprint upon a piece of paper against which it is pressed. The wheel is rotatably mounted upon an axle 12 secured at the outer ends of fork arms 13 and 14 between which the wheel is positioned. This 35 fork is suitably secured at one end of a handle 15.

The stamp portion 11 of the wheel is automatically inked by incorporating an inking mechanism within the handle 15 of the device. In Fig. 2 one form of such a mechanism is shown, comprising a tubular ink reservoir 16 extending the length of the handle and closed at its outer end by a removable cap 17. Positioned within the opposite opened end of the reservoir which

terminates between the arms 13 and 14 of the fork is a distributing brush 18. The tuft of this brush normally bears against the surface of the tire 11 of the wheel and is supplied with ink from the reservoir 50 through a central supply duct 19.

In operation, the embossed surface of the tire 11 may be supplied with ink and thereafter brought to bear against the surface of a check. As the wheel is rolled along the 55 check, the spaces between the indicia upon the check will be filled by the mark made by the embossed portion of the tire. This will prevent additional figures from being added to the check and thus prevent the amount 60 of the check from being raised, and will also protect the payee of the check, in case of its being lost or stolen, from the substitution of another name.

It will thus be seen that this device is 65 decidedly simple in its construction and will act effectively to produce the result desired.

While I have shown the preferred construction of my check protector as now known to me, it will be understood that 70 various changes in the combination, construction and arrangement of parts may be made by those skilled in the art without departing from the spirit of my invention as claimed. 75

I claim:

A handle, a tubular ink reservoir mounted longitudinally in the handle, a removable cap at the outer end of the handle for closing the reservoir, a supply duct extending 80 from the inner end of the reservoir, parallel forks extending from the inner end of the handle, a printing wheel mounted between the forks, and a brush leading from the duct and bearing against the printing surface on the periphery of the printing wheel to ink the printing surface. 85

In testimony whereof I have signed my name to this specification.

G. D. STINSON.
